UNITED STATES PATENT OFFICE.

ARTHUR A. JOHNSON, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,304,776.

Specification of Letters Patent. Patented May 27, 1919.

Application filed November 10, 1917. Serial No. 201,257.

To all whom it may concern:

Be it known that I, ARTHUR A. JOHNSON, a citizen of the United States, residing in borough of the Bronx, in the county of 5 the Bronx, city and State of New York, have invented certain new and useful Improvements in Combined Type-Writing and Computing Machines, of which the following is a specification.

10 This invention relates to combined type-writing and computing machines.

To obtain the cross-totals of numbers type-written in different columns, it has been the custom to employ a cross-totalizer, which 15 has usually been provided with means to connect and travel intermittently with the typewriter carriage.

For this purpose, tappets have been provided on the typewriter carriage, for picking up the cross-totalizer at intervals determined by the locations of the tappets, and, for convenience, these tappets have been formed upon the tabulator stops which are 20 customarily used for jumping the carriage 25 to a computing zone.

The tabulator stops are also employed for positioning the carriage in non-computing zones; and the non-computing zone-stops have not been provided with the tappets for 30 controlling the cross-totalizer.

Hence, it has heretofore been found necessary to provide two kinds of tabulator stops in a machine of this character, one kind for computing zones, and one kind for non- 35 computing zones; and it has also been necessary for the operator to use great care to place the right stop in the right place upon the typewriter carriage.

In other words, the ordinary tabulator 40 stops on the typewriter carriage could not be used for reciprocating the cross-totalizer during the movement of the carriage, but were specially made with lugs for this purpose, and it was necessary for the operator 45 to see that the proper stop with the lug was placed in proper position on the typewriter carriage for a computing zone.

The present invention provides means whereby all the stops may be uniform, 50 whether used for one purpose or the other, thus avoiding care and time occupied in selecting and placing the stops. To bring about this result, the connections between the cross-totalizer and the carriage, which are 55 normally out of position to be engaged by

the tabulator stop, are moved into effective positions as the typewriter carriage enters the computing zone. This movement is preferably controlled by the movement of the column-totalizer, which is usually also carried by the typewriter carriage, for vertical computation. 60

Since the stops may be all alike, the still greater advantage is gained of utilizing a "key-set" tabulator mechanism, in which the stops (one of which is provided for each letter-space of the typewriter carriage) are settable by a key arranged at the keyboard of the machine. The position of the carriage determines which stop shall be set. In 70 order to set these stops, the operator first positions the typewriter carriage at the desired point, and then depresses the key for setting the stops. 65

According to this invention, a cam carried by said column-totalizer may, as a computing zone is approached, cause the connections from the cross-totalizer to be moved up into position to be engaged by one of the carriage tabulator stops that has been key-set in the described manner. The cross-totalizer is then advanced by the typewriter carriage until the latter passes out of the computing zone, at which time said cam on the column-totalizer may cause the connections to move away from the tabulator stops. The cross-totalizer and its connections return to normal positions. This operation 85 may be repeated at each computing zone. 80

Heretofore, in some instances, the cross-totalizer has been reciprocated by a direct connection to the column-totalizer, but it has been found that the column-totalizer should not be thus burdened, as it is a very sensitive part of the machine. This difficulty is overcome by my invention, since the cross-totalizer may be reciprocated by tabulator stops which are or may be universally alike. A more rigid and less sensitive part of the carriage mechanism serves to move the cross-totalizer, although the present invention maintains the control of the cross-totalizer from the column-totalizer, inasmuch as the column-totalizer simply moves an interpo- 90 nent which causes the cross-totalizer to be moved by the typewriter carriage. It will be 95 seen, therefore, that there are two important features included in the present invention, first, to cause the cross-totalizer to be moved by the tabulator stops of the typewriting ma- 100 105 110

chine, under the control of the column-totalizer, and second, that a key-set decimal tabulator may advantageously be used for reciprocating the cross-totalizer.

5 The operator sometimes desires to compute in the column-totalizer without computing in the cross-totalizer; and for this purpose the train of connections between the column-totalizer and the connections from the cross-totalizer may be broken at the will of the operator. This may be accomplished by mounting the cam on the column-totalizer so that it can be moved at will out of the range of the follower.

10 15 This invention is illustrated in connection with the disclosures of my application No. 112,645, filed August 2, 1916, and Pitman applications Nos. 24,390, filed April 28, 1915, and 186,098, filed August 14, 1917.

20 Other features and advantages may hereinafter appear.

In the accompanying drawings,

25 Figure 1 is a side view in elevation, partly broken away to show the underlying structure, and with parts omitted to simplify the showing.

30 Fig. 2 is a skeleton, perspective view, showing the control of the traversing of the cross-computing unit traveling element from the vertical column-computing units.

35 Fig. 3 is a fragmentary rear view in elevation, showing the pick-up hook in the train of connections between the carriage and the cross-computing unit, as in its depressed inactive position out of range of the tabulating stops carried by the carriage.

40 Fig. 4 is a detail view, showing part of the elements disclosed in Fig. 3, with the pick-up hook raised to its active position engaged by one of the set tabulating stops carried by the carriage.

45 Fig. 5 is a detail view in front elevation, showing one of the vertical column-computing units just before it has come into engagement with the shifting train of linkages to bring about a movement of the pick-up hook into range of the corresponding zone-controlling stop.

50 Numeral keys 1 and alphabet keys 2 depress key levers 3 to rock bell cranks 4, so as to swing type-bars 5 up rearwardly against the front side of a platen 6 mounted to rotate on a carriage 7. The carriage 7 travels step by step under the control of an escapement mechanism, which includes a rack bar 8 pivotally mounted on the carriage 7 and normally engaging a pinion 9. The pinion 9 is connected by the usual one-way pawl-and-ratchet mechanism, not shown, to an escapement wheel 10, which is controlled in its movements by fixed and loose dogs 11 and 12. The dogs 11 and 12 are rocked into alternate engagement with the escapement wheel 10 at each operation of a character key, by means of a universal frame 13, which,

in turn, is operated by heels 14 provided on each of the type-bars 5.

5 In addition to step-by-step letter-feed movements, the carriage 7 has jump or tabulating movements to skip from one major column or zone to another major column or zone. For this purpose, there is provided tabulating mechanism, which includes decimal tabulating keys 15 connected in a manner common to Underwood standard typewriters, to thrust plungers 16 up into the path of set stops 17 carried by the typewriter carriage 7. The tabulating mechanism is of the key-set type in which there are provided a series of identical stops 17, 75 one for each letter-space of the typewriter carriage 7. These stops 17 are normally held in a raised inactive position on a bar 18, carried by the carriage 7, by spring-pressed 80 detents 19. The stops 17 are settable individually by bringing the typewriter carriage to the letter-space at which it is desired to have a major column or zone and then depressing a setting key 20. This setting mechanism is more particularly described and 85 claimed in the patent to Doane No. 1,157,683, 90 patented October 26, 1915. The action of this key-setting mechanism consists in depressing the key 20 to rock a key lever 21 which thrusts down on a link 22 to rock a 95 bell crank 23. The bell crank draws down on a setting link 24, which has an overhang 25 projecting over the series of stops 17 corresponding to the printing point of the carriage 7. This overhang 25 depresses the 100 particular stop 17 corresponding to the bringing of the required zone or major column to the printing point of the typewriter. The stops 17 are of uniform character and may determine solely typewriting zones or 105 combined typewriting and computing zones in a manner more fully described hereinafter.

Considering the computing mechanism, the numeral keys 1, in addition to printing the digits, may also compute them and run them up into totalizers or computing units. 110 These computing units include one or more vertical adding heads 26 and one or more cross-adding heads 27. The vertical adding heads 26 form the traveling elements of the 115 vertical column-computing units and are adjustably mounted along a rail 28 connected by a bracket 29 to travel with the typewriter carriage 7. These vertical adding heads 26, by their adjustment on the rail 28, can be 120 made to correspond to any desired group of letter-spaces or digit columns of the typewriter carriage 7, and thus with any desired major column or computing zone of the typewriter carriage 7. The adding heads 26 125 travel step by step with the carriage 7 when in a computing zone relatively to a master wheel 30. The master wheel 30 is driven from the numeral keys 1 by a key-drive valuating or indexing mechanism in a manner 130

more particularly described in applications Nos. 24,390 and 186,098, above mentioned. Similarly, the computing wheels of the cross-adding head 27 are driven by a master wheel 31, which is also connected to be simultaneously driven with the master wheel 30 by the numeral keys 1.

The adding head 27, which forms the traveling element of the cross-totalizer or computing unit, is not directly connected to travel with the typewriter carriage 7 as are the vertical adding heads 26. This traveling element of the cross-totalizer is connectible indirectly to travel with the carriage 7, so as to move intermittently with the carriage 7 and with the vertical adding heads 26. In this way the cross-computing unit can compute in individual synchronism with several of the vertical column-computing units,—with either, all, or some of them.

Considering this traversing mechanism for the traveling element of the cross-computing unit, the cross-adding head 27 is adjustably mounted on a computing carriage 32, which may be connected to be advanced and returned by a bell crank 33, which may be operated to rock about a vertical axis by a lever 34. The lever 34 may be connected to be operated by a hook 35, and the hook 35 may be picked up by certain of the set stops 17 and traversed step by step with the advancing movement of the carriage 7. This train of connection, including the parts 33, 34 and 35, may act in an advancing direction against the tension of a spring 36 which quickly returns the traveling element 27 when the hook 35 is disconnected from one of the stops 17 which picked it up.

Normally, the hook 35 is in a depressed position out of reach of all of the stops 17, even those which are set to determine major column or zonal positions of the typewriter carriage 7. To bring this hook 35 within range or reach of certain ones of the set stops 17, each of the vertical column-adding heads 26 is provided with a synchronizing cam 37 which determines the computing activity of the cross-adding head 27. The cam 37 is in the form of a rail having a length greater than the number of digit columns in a computing zone, and also greater than the number of computing wheels of different denominations in the cross-adding head 27, so that the hook 35 may be in a raised position to be engaged by a stop 17 in advance of the meshing of the computing wheel of highest denomination with the master wheel. As the carriage 7 advances in a letter-feeding direction, on entering a computing zone, the cam rail 37, when in an active position, engages a one-way acting dog 38 pivotally mounted on a slide 39 and depresses the same so as to rock a lever 40. The lever 40 is connected to pull up on a link 41 so as to

115 rock a lever 42 against the tension of a

spring 43. The lever 42 rocks another lever 44, which thrusts upwardly on a shifter 45. The shifter 45 is in the nature of a slide guided for vertical movement by pins and slots 46, and is provided at its upper end 70 with a head 47 having a slot 48 of at least the capacity of the number of letter-spaces or digit columns of a cross-computing zone. The hook 35 has a pin 49 extending into the slot 48, so that when the cam 37 on the vertical adding head enters a computing zone, in which it is desired to have a cross-computation, the shifter 45 will raise the hook 35 into the path of the particular set column stop 17 corresponding to this zone. This 80 stop will carry the cross-computing traveling element 27 step by step in an advancing direction, with the advancement of the typewriter carriage 7 through the computing zone. Thus, the traveling element 27 of the 85 cross-computing unit will advance in synchronism with the letter-feed movements of the carriage, and also with the step-by-step movements of the traveling element of the vertical column-totalizer or computing unit 90 which controls the cross-computing unit's coming into play. This enables a concomitant computing or cross-adding with a vertical adding as the digits are typewritten.

When the end of a computing zone is 95 reached, the end of the cam rail 37 will come in register with the one-way acting dog, so that the spring 43 may act to return the slide 39 to a raised position and the shifter 45 to a depressed position. This will withdraw 100 the hook 35 out of engagement with the zone-controlling stop 17 which carried it along up to this time, so that the hook 35 is free to return relatively to the typewriter carriage 7. The return movement is accomplished by the spring 36 which also returns the cross-adding head 27, which happens to be the traveling element, to its starting position.

For an advancing movement of the carriage 7, during the writing of a continuous line, the cross-adding head 27 will be moved at times in synchronism with the typewriter carriage 7 for different computing zones, according to the number of the vertical adding heads 26 which have active cams 37 thereon. The return movement of the typewriter carriage 7 does not vibrate the cross-adding head 27 as the dog 38, which is one-way acting, rocks idly about its pivot when one of the active cams 37 passes over it in a return direction. This dog 38 is held by a spring 50 against a pin 51, so that the dog is permitted to rock idly when the typewriter carriage and vertical adding heads 26 pass by it in a return direction, but an active position of the dog 38 is insured when the typewriter carriage moves in an advancing direction.

In some zones in which it is desired to 130

compute in the vertical computing units, it is not desired to also compute in the cross-computing unit; hence the cams 37 are made adjustable between active and inactive positions, so that selective action of the cross-computing unit can be had with respect to the individual vertical computing units. For this purpose, the cam 37 is provided with arms 52, which are slidably mounted by means of pin-and-slot connections 53 on each vertical adding head 26. The active and inactive positions of the cam rail 37, in each case, are determined by a spring detent 54 which engages alternately in notches 55 and 56 provided on one of the arms 52. When the controlling element, including the cam rail 37 and the arms 52, is pulled to its forward position by a handle 57, as indicated by dot-and-dash lines in Fig. 1, the cam rail 37 will be in an inactive position as its line of travel will be out of register with the dog 38. When in its rear position, the line of travel of the cam rail 37 will be in register with the dog 38, so as to be capable of operating the connection and disconnection of the cross-adding head 27 of the typewriter carriage 7.

Considering briefly the operation of the device, it may be assumed that the machine is ready for a new type of work with all of the stops 17 in their unset position. The typewriter carriage 7 is positioned zone by zone to correspond with the active major columns of the particular character of work which it is desired to typewrite and compute. The vertical column-adding heads 26 are adjusted along the rail 28 to positions corresponding to certain of the zones determined by set ones of the stops 17. This need not be all of the zones, as some of the zones selected may be for the purpose of typewriting solely. As the carriage 7 is positioned in each zone, the tabulating stop-setting key 20 is depressed, so as to set the stop 17 corresponding to the lowest denominational position of this zone or major column. This stop will subsequently, through the coöperation of the tabulating mechanism 15, 16, determine the rapid selection of zonal positions of the carriage 7. For such of the computing zones as the vertical adding heads 26 are set, it may also be desired to simultaneously cross-add the numbers run up into these vertical adding heads, whereas, in certain other computing zones, it may be desired that the cross-adding head 27 shall remain silent. For such computing zones as it is desired to have concomitant vertical and cross-adding, the synchronizing rails 37 are shifted to their rearmost active positions. In such computing zones as it is desired to have no cross-adding, the rails 37 on the corresponding vertical adding heads 26 are shifted to their forward inactive positions.

For the beginning of a line of combined typewriting and computing on the worksheets carried by the carriage 7, the cross-adding head 27 will be located to the extreme right of its travel, with the computing wheel of highest denomination thereof just to the right of the master wheel 31, so that this master wheel can rotate idly without driving the computing wheels of the cross-adding head 27, in case the latter is not advanced step by step with the typewriter carriage 7.

The carriage 7 is then positioned for the initial zone or major column by striking one of the decimal tabulating keys 15, which will raise one of the plungers 16 into the path of the first set stop 17. The carriage 7 will jump to the first zone which is determined by the first set stop 17, striking the raised plunger 16. This zone may be solely for the purpose of typewriting, such as writing the date or the character of the item. If such is the case, there will be none of the vertical adding heads 26 located on the rail 28 corresponding to this zone; hence, there will be no vertical computing, and, inasmuch as the cams 37 controlling the cross-computing are on the vertical adding heads, there will also be no cross-computing.

The typewriter carriage 7 may then be jumped to the next zone after the typewriting for the first zone has been accomplished step by step, by striking one of the tabulating keys 15. This will select a particular letter-space or digit column in the next zone. This zone may be solely for the purpose of vertical computing. If so, the rail 37 is in its forward or inactive position. The digits will then be run up solely in the vertical adding head 26, corresponding to the particular computing zone.

The carriage 7, after the digits of this computing zone have been typewritten, may be jumped to the next zone by striking one of the tabulating keys 15. This next zone may be for both vertical computing and cross-computing. If such is the case, the cam 37 on the vertical adding head will be in its active position. As the typewriter carriage 7 comes into this computing zone, the rail 37 will cause the picking up of the cross-adding head 27, by engaging the dog 38 to depress the slide 39, and thus, through the connecting train of linkages, raise the hook 35 in the path of the stop 17 corresponding to this combined typewriting and computing zone. At the striking of the numeral keys to write and compute in this zone, the cross-adding head 27 will advance step by step in synchronism with the typewriter carriage 7 and with the particular vertical adding head 26 which controls its bringing into play. With the striking of the numeral key corresponding to the writing and computing in units place, the digit

of this place will be typewritten and run into the units computing wheels of both a vertical column-adding head 26 and the cross-adding head 27. As the typewriter carriage 7 advances at the return-stroke of the numeral key, this will clear the cam rail 37 from engagement with the dog 38, causing the hook 35 to be withdrawn from connection with the set stop 17 which has been carrying the hook along with the typewriter carriage 7. With the disconnection of the train of connection to the cross-adding head 27, the spring 36 will return the head to its initial position just out of register with the master wheel 31.

In this way, the complete typewritten and computing line is done, the cross-adding head 27 being picked up a number of times, so as to act in synchronism with several of the vertical adding heads 26. In this way a combined typewriting and computing action can be had, in which the numbers as typewritten are added vertically and also certain of them added horizontally. Also, this action is enabled by a series of uniform or identical stops 17 which are of a convenient key-set character and which are uniformly set. The selection of which ones of the actively set stops shall be the cross-computing zone-controlling stops is accomplished by the cam rails 37 on the vertical adding heads 26.

Variations may be resorted to within the scope of the invention, and portions of the improvements may be used without others.

Having thus described my invention, I claim:

1. The combination with a typewriter carriage, of one or more vertical column-computing units having a traveling element connected to travel with said carriage, a cross-computing unit having a traveling element, and mechanism for controlling the connection, at a point other than said vertical column-computing units, of the traveling element of the cross-computing unit to said typewriter carriage from said vertical computing units.

2. The combination with a traveling carriage, of a plurality of active zone-controlling stops of uniform character, some corresponding to typewriting zones and others to combined typewriting and computing zones, as determined by the position of said carriage, a cross-computing unit having a traveling element, a pick-up train for connecting said traveling element to said carriage, and automatic means for causing said train to selectively connect to said stops, so that active stops of the same form can selectively determine zones of different character.

3. The combination with a traveling carriage, of a cross-computing unit having a traveling element, uniform stops having the same range when active for controlling se-

lectively either typewriting or combined typewriting and computing zones, vibrating means for said traveling element including a pick-up connection for engaging certain of said stops to traverse said traveling element with said carriage, said connection being normally out of range of all said stops including the active stops, and means dependent on the travel of said carriage for bringing said connection and some of the active stops into range of each other to determine computing zones.

4. The combination with a traveling carriage, of a plurality of computing units having traveling elements, an indirect connection from one of said traveling elements to said carriage having a part normally out of range of joinder of the last-mentioned traveling element with said carriage for all positions of the carriage, and automatic means dependent on the position of the traveling element of another of said computing units for controlling the bringing of said part into effective range of joinder, so that the active connection of the traveling element of one of said computing units to said carriage will be controlled indirectly from another of said computing units.

5. The combination with a traveling carriage, of a series of uniform stops for determining the zonal positions of said carriage, a computing unit, and automatic mechanism selectively made effective or ineffective, for determining the activity of said computing unit by identical stops identically adjusted at different positions along said carriage.

6. The combination with a carriage traveling to determine typewriting and computing zones, of one or more vertical computing units having traveling elements, a cross-computing unit having a traveling element, a plurality of stops carried by said carriage, a train of connections to said traveling element of said cross-computing unit normally out of reach of said stops, and means for shifting said train of connections into reach of one of said stops when a vertical column-computing unit's traveling element comes into a computing zone as determined by the travel of said carriage.

7. The combination with a traveling carriage, of a series of uniform stops settable selectively and individually to set positions which are uniform to determine the zonal positions of said carriage, one or more computing units, and additional means associated with the computing units settable to determine automatically which of the set ones of said uniform stops shall determine computing zones.

8. The combination with a traveling carriage, of a series of identical stops settable individually the same distance in the same way to determine zonal positions of said carriage, a computing unit, a train of con-

nections operated by some of said identical stops when set, to bring in play said computing unit, so as to determine computing as well as typewriting zones, the rest of the 5 set stops determining typewriting zones, and a plurality of elements extraneous to said stops for selecting certain set stops to control the activity thereof to operate said connections to bring in play said computing unit.

10 9. The combination with a traveling carriage, of a series of identical stops settable individually the same distance in the same way to determine zonal positions of said 15 carriage, a computing unit, a train of connections operated by some of said identical stops when set, to bring in play said computing unit, so as to determine computing as well as typewriting zones, the rest of the 20 set stops determining typewriting zones, a plurality of elements extraneous to said stops for selecting certain set stops to control the activity thereof to operate said connections to bring in play said computing unit, and 25 means individual to each of said elements enabling it to be silenced.

10 10. The combination with a traveling typewriter carriage, of a series of identical tabulating stops for said carriage, one for 30 each digit or letter-space thereof, said stops being selectively settable identically from inactive positions to individual active positions to determine typewriting and combined typewriting and computing zones, a 35 computing unit, mechanism operated by some of said stops when set for determining as well as a typewriting zone the activity of said computing unit for a computing zone, and a plurality of computing zone-controlling 40 members on said carriage for governing the effectiveness of said identical stops when set to determine the activity of said computing unit.

11 11. The combination with a traveling carriage, of a plurality of vertically computing units, of a cross-computing unit, a plurality of stops carried by said carriage, connections enabling the control of the operation 45 of said cross-computing unit from said stops, and a cam on each of said vertically computing units for controlling the effectiveness of said stops and said connections to bring 50 said cross-computing unit into play, so that the synchronizing of the action of said cross-computing unit with the vertically computing units can be controlled from said vertically computing units.

12 12. The combination with a traveling carriage, of a plurality of zone-controlling 55 stops carried by said carriage, a plurality of vertically computing units, a cross-computing unit, connections controlled by said stops for governing the activity of said cross-computing unit, shifting mechanism for bringing 60 said connections into play with some of

said stops, a cam on each of said vertically computing units for operating said shifting mechanism, and means for adjusting said cams individually into and out of effective range of said shifting mechanism, whereby 70 the activity of said cross-computing unit as controlled from said stops and said vertically computing units may be selectively determined from said vertically computing units by the adjustment of said cams. 75

13. The combination with a traveling carriage, of a plurality of identical stops settable individually to determine zonal positions of said carriage, a cross-computing unit having a traveling element, a train of 80 connections to said traveling element including a pick-up hook normally out of reach of said zone-controlling stops when actively set, and automatic means dependent on the travel of said carriage for shifting said hook within reach of some of said stops, so as to give 85 computing actions of said cross-computing unit by advancing the traveling element thereof with said carriage at several points in the travel of said carriage according to a predetermined plan.

14. The combination with a traveling carriage, of a plurality of identical carriage-carried pick-up stops settable to determine zonal positions of said carriage, a cross-computing unit having a traveling element, 95 a train of connections for traversing said traveling element including a pick-up hook normally out of reach of said pick-up stops, a shifter having a sliding engagement with 100 said hook of at least the range of travel of said traveling element, and means controlled from said carriage for operating said shifter at intervals in the travel of said carriage to bring said hook within the range of said 105 stops carried by said carriage, whereby said traveling element may be traversed from said stops and thus from said carriage.

15. The combination with a traveling carriage, of carriage-carried tabulating stops 110 for determining zonal positions of said carriage, a cross-computing unit having a traveling element, a train of connections to said traveling element including a pick-up hook normally out of reach of said stops, shifting 115 means for bringing said hook within reach of said stops including a slide having a one-way acting dog thereon, one or more vertically computing units mounted to travel with said carriage, and an active cam on 120 certain of said computing units engaging said dog to operate said shifting means, so as to connect up the traveling element of said cross-computing unit with the stop corresponding to the vertically computing unit 125 in action.

16. The combination with a traveling carriage, of carriage-carried stops for determining zonal positions of said carriage, a cross-computing unit having a traveling ele- 130

ment, connections for traversing said element from said stops, one or more vertically computing units, controlling means for said connections, and a cam on each of said vertically computing units for operating said controlling means, having an effective length corresponding to at least the number of computing wheels in said cross-computing unit, and proportionate to the travel of said traveling element of said cross-computing unit.

17. The combination with a typewriter carriage having individually settable parts carried thereby, of a cross-computing unit, a vibrating train of connection to said computing unit to be operated from said carriage a plurality of times during a single run of said carriage, having a normal position clear of the path of travel of said carriage and the parts carried thereby, and a series of devices adapted to be settable on said carriage to automatically determine when said connection shall be brought into said path.

18. The combination with a traveling typewriter carriage having parts carried thereby, of a cross-computing unit, a train of connections for vibrating said computing unit from said carriage a plurality of times during a single advancing line-movement of said carriage, said train of connections having a normal position clear of the path of travel of the carriage and the parts carried thereby, and shifting means active solely on the advance of said carriage and inactive on the return of said carriage, for bringing said train of connections into the path of travel of parts carried by said carriage, so that said train of connections will stand entirely clear of said carriage and the parts carried thereby during a return movement of the carriage, so as to remain idle.

19. The combination with a typewriter carriage, of a sub-carriage, a pick-up device traveling with said typewriter carriage, a train of mechanism connected to said sub-carriage, and an element traveling with said typewriter carriage adapted to render said train of mechanism effective to be engaged by said pick-up device.

20. The combination with a traveling carriage, of a plurality of identical carriage-

carried pick-up members adapted to be set, a cross-computing unit having a traveling element, a train of connections for traversing said traveling element including a pick-up hook normally out of reach of said pick-up members, a shifter having a sliding engagement with said hook of at least the range of travel of the traveling element, and settable means controlled from said carriage for automatically operating said shifter at intervals in the travel of said carriage to bring said hook within the range of said members carried by the carriage, whereby the traveling element may be traversed by said members.

21. The combination with a traveling carriage, of carriage-carried stops for determining zonal positions of said carriage, a cross-computing unit having a traveling element, connections for traversing said element from said stops, a plurality of vertically computing units, controlling means for said connections, and a cam on each of said vertically computing units adapted to be set to be effective or ineffective to operate said controlling means.

22. The combination with a traveling typewriter carriage having parts carried thereby, of a cross-computing unit, a train of connections for vibrating said computing unit from said carriage a plurality of times during a single advancing movement of the carriage, said train of connections having a normal position clear of the path of travel of the carriage and the parts carried thereby, a vertically computing unit, shifting means adapted to bring said train of connections into the path of travel of parts carried by said carriage, a device associated with the vertical unit for operating said shifting means to carry the connections into the path of parts carried by the carriage, said device adapted to be effective during the forward travel of the carriage and ineffective during the return travel thereof, and connections whereby said device may be made ineffective at will.
